UNITED STATES PATENT OFFICE.

ERNEST M. GUILLAUME, OF JACKSON, MICHIGAN, ASSIGNOR TO THE FELTERS COMPANY, INC., OF BOSTON, MASSACHUSETTS, A CORPORATION OF MASSACHUSETTS.

WINDOW CHANNEL.

Application filed March 14, 1924. Serial No. 699,277.

To all whom it may concern:

Be it known that I, ERNEST M. GUILLAUME, a citizen of the United States, residing at Jackson, in the county of Jackson and 5 State of Michigan, have invented certain new and useful Improvements in Window Channels, of which the following is a specification.

My invention relates to improvements in 10 window channels.

The object is to provide a built-up channel composed of soft pliable material adapted to embrace the edges of a window or window-pane sufficiently tight to exclude air, 15 dust, and rain, and prevent rattling and noise, while at the same time permitting the window or pane to be slid to open or close the window.

In the accompanying drawings:

20 Fig. 1 is a transverse section of the device before it is fastened to the back strip;

Fig. 2 is a transverse section of the completed article;

25 Fig. 3 shows a similar view with the parts assembled and in position in a window-frame with the window-pane in the channel, the back strip being of reduced width;

Fig. 4 is a rear view of the back strip with 30 a part broken away; and

Figs. 5 and 6 show slightly modified forms.

My present channel includes two filler strips 1, preferably of felt enclosed in a covering 2 of felt to form the side walls of the 35 channel when bent into U-shape as shown in Fig. 2.

The covering 2 in this form completely encloses the strips 1, and forms a double layer through the center 3, as illustrated.

40 When thus bent, the two rows of stitching shown straight in Fig. 1 are pulled at an angle, or diagonally, as indicated by the numeral 4 in Figs. 2 and 3, and by means of two more rows of stitching 5 the back strip 45 6 is attached. This back strip 6 may be the same width as the channel, and the edges flush with the outer edges of the wall of the channel as shown in Fig. 2, or of less width as shown in Fig. 3, if desired, according to 50 the requirements of the user.

When made in this form, two stitching operations are necessary, first, partly to form the article as viewed in Fig. 1; and the second operation including the stitches 5 as 55 illustrated in Figs. 2 and 3. The construc-

tion illustrated in Fig. 5 is like that shown in Fig. 2 except that the entire article is made in one stitching operation instead of two as shown at 7; in other words, the stitching 4 is omitted.

In Fig. 6, a similar construction is shown, except that here the back strip 6 is enclosed in the outer covering 2, instead of being on the outside, but the parts are assembled and held together by a single stitching operation 65 as shown at 7.

In these various constructions, there is no reinforcing at the juncture of the side and back wall tending to force the side walls inwardly toward each other. On the contrary, there is no reinforcing, and there is no tendency to force the side walls inwardly toward each other, the construction in reality being such that the result is just the opposite, or in other words tends to force the side 75 walls away from each other.

The window frame 9 has the usual groove 10, the sides of which confine and form lateral support for the walls of the channel as viewed in Fig. 3, thus making it quite unnecessary to rely upon stitching for this purpose. The numeral 11 represents the window glass which fits and slides within the channel.

80 In this way, a simple but effectual channel is formed of a plurality of strips of flexible and preferably fibrous material, such as felt, so assembled that the side and bottom walls form the three sides of the channel, and the sides of the window-frame 90 channel 10 hold the side walls against the window or glass 11, with sufficient frictional pressure to exclude air, dust, rain, and prevent rattle.

I claim:

1. A window channel including side wall filler strips, a covering surrounding and enclosing said filler strips and forming a double walled bottom, and a backing strip secured to and for reinforcing said bottom.

100 2. A window channel including side wall filler strips, and a covering enclosing the filler strips and stitched externally thereof and bent into a substantially U shape thereby drawing the stitching diagonally.

105 3. A window channel including side wall filler strips, a covering enclosing the filler strips and stitched thereto and bent into a substantially U shape thereby drawing the stitching diagonally, and a backing strip se-

cured to the covering for holding the parts in proper position.

4. A window channel including side wall filler strips, and a covering enclosing the 5 filler strips and stitched externally thereof and bent into U-shape, whereby the stitching is drawn at an angle or diagonally, a back strip, and straight stitching extending through the double layer at the bottom of 10 the channel and the back strip.

5. A window channel including side wall filler strips, a covering surrounding and enclosing said filler strips and forming a double walled bottom, stitching extending 15 through the covering, said covering being bent, substantially into U shape thereby drawing the stitching diagonally, and a backing strip secured to the covering for holding the parts in proper position.

20 6. A window channel including filling means, a covering therefor, the entire device being bent to form an approximately U-shaped channel, a backing strip and stitching entirely within the channel and extending 25 through the backing strip for holding the parts together.

7. A window channel including side wall filler strips and a covering therefor bent to form an approximately U-shaped channel, a backing strip and stitching entirely within 30 the channel and extending through the backing strip for holding the parts in their channel formation.

8. A window channel including filling means, a covering entirely enclosing said filling means, a backing strip and stitching located within the inner confines of the channel and extending through the backing strip for holding the covering in its position about the filling means.

9. A window channel including filling means, a covering enclosing said filling means and extending across the back of the channel, the edges of said covering extending inwardly on the back side of the channel, and 45 stitching extending through the layers of material forming the bottom of the channel and including the edges of the covering for holding said covering about the filling means.

In testimony whereof I affix my signature.
ERNEST M. GUILLAUME. 50
